UNITED STATES PATENT OFFICE.

WILLIAM W. LOWREY, OF RICHMOND COUNTY, NEW YORK.

DESIGN FOR A BOTTLE.

SPECIFICATION forming part of Design No. 25,388, dated April 14, 1896.

Application filed March 13, 1896. Serial No. 577,064. Term of patent 3½ years.

To all whom it may concern:

Be it known that I, WILLIAM W. LOWREY, a citizen of the United States of America, and a resident of Richmond county, Staten Island, 5 New York, have invented a new and useful Design for Glass Bottles, of which the following is a specification.

In the drawings, Figure 1 represents a front elevation of a glass bottle, showing my design.

Fig. 2 represents a side elevation of Fig. 1. Fig. 3 represents an inverted plan.

The leading feature of my invention consists in a glass bottle having four convex planes forming the four sides thereof. Said 15 four planes consist of a line beginning with an acute curve at the base and diverging slightly by a long curve upwardly, thence to an acute curve, joining, as it does, with a long and sweeping curve, extending at right angles to the vertical planes aforesaid, the latter of which terminate in a curve-shaped tablet, 20 the top of which connects with a cylindrical ring, from which arises the neck of the bottle in the usual way.

Similar letters refer to similar parts throughout the drawings, in which—

A represents the vertically-diverging convex planes, whose surfaces are formed by the abrupt curve B, long curve C, abrupt curve D, and the right-angled curve arranged at right angles to the vertical sides aforesaid. Said convex sides terminate at the base into a rectangular-shaped base E and at the top with a curved tablet F, upon which rests the cylindrical ring G, from which extends the neck 35 of the bottle in the usual way.

What I claim is—

The design for a glass bottle substantially as shown and described.

In testimony that I claim the foregoing as 40 my invention I have signed my name, in presence of two witnesses, this 18th day of January, 1896.

WILLIAM W. LOWREY.

Witnesses:

D. S. DOLBEAR,
J. A. HURDLE.
